Patented Mar. 9, 1965

200,537

DENTAL MIRRORS OR SIMILAR ARTICLES

Milton V. Sanden, 1448 Galena St., Aurora, Colo.

Filed Apr. 8, 1964, Ser. No. 79,401

Term of patent 14 years

(Cl. D24—1)

FIG. 1

FIG. 2

I claim:

The ornamental design for dental mirrors or similar articles, substantially as shown.
